UNITED STATES PATENT OFFICE

DAVIS A. CABLE, OF CANTON, OHIO, ASSIGNOR TO UNITED STATES QUARRY TILE COMPANY, OF PARKERSBURG, WEST VIRGINIA, A CORPORATION OF DELAWARE

TILE-MAKING PROCESS

Application filed October 29, 1928. Serial No. 315,609.

The invention relates to making ceramic products, and more particularly to making tile, slabs, blocks, and the like, for use as refractories or for exterior or interior walls and floors of buildings and the like, which may be of the type sometimes known as quarry tile, and the dimensions of each of which may be in the ratio of substantially six inches square by three quarters of an inch thick; and this application is a continuation of the common subject matter in my copending application filed December 29, 1927, Serial No. 243,325 for the same invention.

In order to meet trade requirements, particularly when the tile are to be used for the interior finish of buildings, all the faces and edges of the tile must be true and in the desired angular relationship with each other. That is to say, the intersecting edges and faces of an ordinary unbevelled square tile should all be at right angles with each other.

According to the usual method of manufacturing quarry tile, which includes forming, drying, and burning the tile, it has been the practice to form the tile, from damp clay, shale or a mixture of ceramic materials in such a manner that after drying and burning, and the shrinkage incidental thereto, the faces and edges of some of the finished tile may be true enough for use.

The tile made according to that method however, include a large number which are untrue, warped and unfit for any use, and a large number which are only fit for a limited use.

Other methods of manufacturing clay products other than quarry tile include forming, drying, repressing, and burning; or include forming, drying, repressing, planing, repressing, and burning; and it has been the practice to form the clay products from damp clay, shale or a mixture of ceramic materials in such a manner that after the repressing and burning operations, and the shrinkage incidental thereto, the faces and edges of the finished products may be sufficiently true for the uses to which they are to be put.

According to the usual method which includes a repressing of plastic material the

drying operation is carried out for a time only sufficient to semi-dry the material, the mixture being in a plastic state after the drying operation has been complete. This is necessary for the reason that the next step is a repressing step which includes reforming the plastic material in pressure molds. It is impossible to carry out the repressing step unless the material is in a plastic state, for if the material has passed beyond the plastic state or limit, it will be hard and brittle and will be crushed or broken by the repressing operation rather than being reformed or repressed.

Accordingly, the objects of the present invention involve an improved tile making process, whereby quarry tile and the like may be made true and accurate for any desired use, and by which a large proportion of the tile made according to the improved process may be used; thereby avoiding the waste heretofore incurred in warped and untrue tile.

These and ancillary objects are attained by the use of the improved tile making process hereinafter set forth in detail, and which may be stated in general terms as including, first, forming a block from moist ceramic material, then drying the block beyond the plastic limit to eliminate substantially all of the moisture so that the block will be hard and brittle, thereby effecting substantially all of the drying shrinkage of the block, then truing the block preferably by the use of a suitable grinding or abrading machine, and finally burning the block as a final step in the making of a substantially true and accurate block for use as a tile or the like.

One of the tile, and an arrangement of apparatus adapted for carrying out the improved process for making the same are illustrated in the accompanying drawing forming part hereof, in which

Figure 1 is an isometric view of one of the tile; and

Fig. 2 a fragmentary diagrammatic plan view illustrating the apparatus for carrying out the improved process. Similar numerals refer to similar parts throughout the several views.

As an example of one type of product adapted to be made by the improved process, the quarry tile 10 for use more particularly for the exterior or interior finish of buildings, may each have finished dimensions of substantially six inches square by three-quarters of an inch thick.

The tile 10 are made by the improved method hereof, by forming blocks 10' of moist clay, shale, or a mixture of any desired ceramic materials, in a forming machine indicated diagrammatically at 11, and which may be of any well known construction, and may include for example means for forcing a column of clay outwardly from a nozzle and for severing the blocks 10' from the column by means of wire cutters or the like.

The blocks 10 may then be piled upon a car 12 and transported thereon through a drier 13, in which substantially all of the total free moisture in the blocks is removed, rendering the blocks brittle, thereby effecting substantially all of the drying shrinkage usually incurred in the manufacture of ceramic materials.

The dried brittle blocks 10'' are then wheeled on their car 12 to a truing machine indicated diagrammatically at 14, which may be of any desired type, and more particularly may be of a type in which the blocks are subjected to grinding or abrading in order that they may be effectually trued without breaking, cracking or otherwise destroying the dried brittle block. The truing machine 14 is adapted to accurately trim the faces of the dried brittle block 10'' and to deliver the dried and trued block 10''', which may be transported as for example by a belt conveyor indicated diagrammatically at 15 to a periodic kiln 16 for burning, or which may be transported on another car 12''' to a continuous kiln 17 for burning.

A very large proportion of the resulting tile 10 made by this method of manufacture, have edges and faces which are true, accurate and in the desired angular relationship with each other, and are accordingly adapted for any desired use.

The ceramic material issuing from the forming machine 11 contains a large proportion of moisture which is in two forms, mechanically combined moisture and chemically combined moisture. In the drying operation the mechanically combined moisture will be driven off so that the blocks 10'' contain a very low percentage of mechanically combined moisture and are in a non-plastic brittle state. The chemically combined moisture and the remaining mechanically combined moisture are driven off during the burning operation.

Ceramic material which has been dried but which still contains sufficient moisture to

retain plasticity is known in the industry as semi-dried material and may be readily and easily molded or repressed. When the moisture content of the ceramic material is reduced below the plastic limit it is brittle, thus being in a state in which it cannot be molded or repressed without breaking. The material which has been dried beyond the plastic limit is known as partially dried material for it still contains a small proportion of moisture, but, being brittle it may only be worked on as by grinding or abrading, or

If the material which has been dried has practically no mechanically combined moisture then that material is known in the industry as bone dry material. Thus bone dry material and partially dry material are materials beyond the plastic limit and are brittle and cannot under any conditions be subjected to the step known in the ceramic industry as repressing.

I claim:

1. The method of making tile and the like which includes forming a block of moist material, drying the block to beyond the plastic limit, truing the block, and then burning the block.

2. The method of making tile and the like which includes drying a moist block to beyond the plastic limit, truing the block, and then burning the block.

3. The method of making tile and the like which includes truing a block dried beyond the plastic limit, and then burning the block.

4. The method of making tile and the like which includes forming a block of moist material, drying the block to beyond the plastic limit, grinding the block edges and faces to true the same, and then burning the block.

5. The method of making tile and the like which includes forming a block of moist material, drying the block until brittle, truing the block, and then burning the block.

6. The method of making tile and the like which includes drying a moist block until brittle, truing the block, and then burning the block.

7. The method of making tile and the like which includes truing a dried brittle block, and then burning the block.

8. The method of making tile and the like which includes forming a block of moist material, partially drying the block, truing the block, and then burning the block.

9. The method of making tile and the like which includes partially drying a moist block, truing the block and then burning the block.

10. The method of making tile and the like which includes truing a partially dried block, and then burning the block.

11. The method of making tile and the like which includes forming a block of moist ma-

terial, bone drying the block, truing the block, and then burning the block.

12. The method of making tile and the like which includes bone drying a moist block, truing the block and then burning the block.

5 13. The method of making tile and the like which includes truing a bone dried block, and then burning the block.

14. The method of making tile and the like 10 which includes drying a moist block beyond the plastic limit, grinding the block edges and faces to effect the proper angular relationship between the intersecting edges and faces, and then burning the block.

15. 15. The method of making tile and the like which includes bone drying a moist block, grinding the faces and edges of the block so as to make the planes of the intersecting faces and edges at right angles to each other.

20 16. The method of making tile and the like which includes drying a moist unbevelled block until brittle, truing the block by grinding the intersecting faces and edges, and then burning the block.

25 17. The method of making tile and the like which includes partially drying an unbevelled moist block, grinding the edges and faces of the block so as to true the same and produce the proper angular relationship be- 30 tween the planes of the intersecting edges and faces, and then burning the block.

In testimony that I claim the above, I have hereunto subscribed my name.
